JET WASHING APPARATUS

Artie F. McFarland, Houston, Tex., assignor, by direct and mesne assignments, to McFarland Manufacturing Corporation, Houston, Tex., a corporation of Texas

Application September 4, 1944, Serial No. 552,623

4 Claims. (Cl. 299—58)

1

This invention relates to jet washing apparatus and has for its general object the provision of such an apparatus which will provide an efficient and thorough high pressure jet washing action.

High pressure fluid jets have in the past been employed for cutting or loosening dirt scale or the like from a surface to be cleansed. Such jets, however, have for the most part been of such a nature that the volume delivered through them was very small, and wholly insufficient to flush off the loosened material once the jet had acted to loosen it. Use of the high pressure jet as a flushing jet is time-consuming and is highly inefficient not only because of the time required but because of the high pressure at which the small volume of fluid is delivered to the work.

It is, therefore, an object of the invention which will provide an apparatus which will result in delivering to the work simultaneously a high pressure small volume jet capable of loosening and cutting dirt from a surface to be cleansed, and a relatively low pressure large volume stream capable of flushing off the loosened material in a highly efficient manner.

It is further an object of this invention to make use of a hydraulic pump arrangement adapted to furnish a relatively small volume of liquid at very high pressure and to at the same time discharge at low pressure a relatively great volume of the liquid which has been used as a power liquid to provide the high pressure liquid supply, so as to employ the high pressure liquid supply for cutting and loosening dirt or the like from a surface to be cleansed and making use of the relatively low pressure waste power liquid for flushing away the substances loosened by the high pressure liquid cutting action.

Furthermore, it is an object of this invention to provide a device capable of producing a high pressure stream of fluid utilizing as a power source a relatively low pressure liquid or gaseous fluid supply.

Other objects and advantages of this invention will become apparent from the following description taken in connection with the accompanying drawings in which is set forth by way of illustration and example one embodiment of this invention.

In the drawing the single figure illustrates diagrammatically and mostly in longitudinal cross-section an apparatus constructed in accordance with this invention.

Referring more in detail to the drawing, the apparatus illustrated may be roughly divided into

2

three parts comprising the main control valve designated by the numeral 1, the hydraulic pump indicated generally by the numeral 2 and the composite nozzle indicated generally by the numeral 3.

It is intended that this invention shall utilize a power fluid which may be compressed air or gas supplied through the conduit 4, or a suitable liquid such as water under relatively low pressure through a supply conduit 5. The liquid which is adapted ultimately to form the high pressure cutting jet may be taken from the supply conduit 5 through a suitable three-way valve 6 when the same is in the position illustrated in the drawing, and thence through the conduit 7 to the main valve 1 or it may be taken from any other source such as a soapy solution through a conduit 8, and thence through the valve 6 and the conduit 7. For this latter purpose the valve 6 would be turned a quarter turn to place the conduits 7 and 8 in communication with each other.

The power fluid received through either of the conduits 4 or 5 will be placed in communication with the main valve through a suitable three way operating valve 9 and a conduit 10, and with the pilot valve which will presently be described, through the valve 9 and a conduit 11.

The slide valve elements 12 and 13, located within the main control valve, are adapted to shift from one extreme position to the other to control the supply of power fluid and the supply of fluid to be raised to high pressure by the hydraulic pump 2. These valve elements 12 and 13 are mounted upon a rod 14 which is slidable longitudinally in either direction through the housing of main control valve 1. One of the slide valves 12 is mounted in a valve chamber 15 within such housing and the other slide valve element 13 is mounted within a second valve chamber 16 in this housing. The rod 14 extends through the end wall of the valve chamber 16 and is attached to a diaphragm 17 so that when pressure is applied to one side of the diaphragm the two slide valves will be moved to one extreme position simultaneously and when pressure is applied to opposite side of the diaphragm the two slide valves will be moved to their opposite extreme positions.

When these slide valves are in the positions illustrated in the drawing, the power fluid will pass through the valve chamber 16 and through the conduit 18 to the right hand ends of the cylinders 19 and 20, respectively, so as to tend to force the pistons 21 and 22, respectively, toward

3

the left as illustrated in the drawing. At the same time, the liquid which is to be used for the high pressure liquid supply will pass through the channel 23 in the slide valve 12 and be conveyed by the conduit 24 to the left hand end of the cylinder 25. As the pistons 21 and 22 are forced toward the left by the power fluid, as above described, the liquid which is to be used as the high pressure fluid supply will be allowed to fill the space within the chamber 25 to the right of the piston 26. Because of the relatively large cross section of the plunger 27, which is interposed between the pistons 21 and 26, as compared with that of the rod 28 which connects the pistons 21 and 22, the volume of liquid drawn into the cylinder 25 to the right of the piston 26 will be much smaller than the volume of power liquid forced into the cylinders 19 and 20 to the right of the pistons 21 and 22.

While the assembly within the hydraulic pump 2 is thus being moved toward the left, liquid from within the cylinder 19 to the left of the piston 21 will be forced outwardly through the conduit 29 and valve chamber 15 to the conduit 38 and thence to the centrally located high pressure port or nozzle 31 within the composite nozzle 3. Because of the relatively small volume of this liquid as compared with the volume of power liquid employed and of the relatively large effective areas of the right hand surfaces of the pistons 21 and 22 as compared with the effective area of the left hand surface of the piston 21, this liquid will be discharged through the nozzle 31 under very high pressure, thus forming a cutting or loosening jet of relatively small volume. At the same time, used power fluid will be discharged from the left hand portions of the cylinders 20 and 25 through conduits 32 and 33, through the channel 34 in the slide valve element 13, and through the conduits 35 and 36 to a relatively large annular nozzle 37 surrounding the jetting nozzle 31. The relatively high pressure low volume strong cutting jet from the nozzle 31 will be directed to substantially the same area as the relatively low pressure large volume flushing stream from the nozzle 37. The result will be that dirt and other substances may be readily loosened by the high pressure low volume jet while such substances may be simultaneously flushed away by the relatively low pressure large volume stream from the nozzle 37.

When the assembly within the hydraulic pump 2 reaches a point adjacent to the left hand extremities of its travel the end of the valve rod 38 will be contacted by the bottom 39 of the bore 40 in the plunger 27, thus shifting this valve rod and the pilot slide valve element 41 toward the left. Before such shifting action, power fluid from the conduit 11 will enter the chamber 42 of this pilot valve and pass from this chamber through the conduit 43 to the right hand side of the diaphragm 17, thus holding the slide valve elements 12 and 13 in the position illustrated in the drawing. At the same time the space to the left of the diaphragm 17 will be vented to the low pressure stream leaving the apparatus, through the conduit 44, the channel 45 of the pilot slide valve element 41 and the conduit 46 which empties into the conduit 36.

When the pilot valve element 41 is shifted to the left as above mentioned, the power fluid from the conduit 11 will then be conducted through the valve chamber 42 and the conduit 44 to the left hand surface of the diaphragm 17. The area to the right of this diaphragm will simul-

taneously be vented to the low pressure discharge from the apparatus, through the conduit 43, the channel 45 and the conduit 46. All this will result in the shifting of the valve elements 12 and 13 to their extreme right hand positions. With the valve elements 12 and 13 in these new positions, the power fluid will be conducted through the valve chamber 16 and the conduits 32 and 33 to those portions of the cylinders 25 and 20 which are to the left of the pistons 26 and 22, respectively. At the same time the spaces within the cylinders 19 and 20 to the right of the pistons 21 and 22, respectively, will be vented through the conduit 18, the valve channel 34 and the conduits 35 and 36 to the low pressure nozzle 31. This will cause the assembly within the hydraulic pump 2 to move toward the right. During this movement high pressure fluid will be forced from that portion of the cylinder 25 which is to the right of the piston 26, through the conduit 24 and the valve chamber 15 to the conduit 30 and the high pressure nozzle 31. A new supply of fluid which is due to form the high pressure fluid supply will simultaneously be drawn in through the conduit 1, the channel 23 in the valve element 12 and the conduit 29 into the space within the cylinder 19 to the left of the piston 21.

When the piston assembly within the pump 2 reaches the position adjacent to the right hand extremity of its travel the head 47 on the end of the valve rod 38 will come in contact with the closure 48 carried by the piston 26, and will shift the pilot valve element 41 back to the position shown in the drawing, whereupon the cycle of operation of the device will be repeated.

Having described my invention, I claim:

1. In a washing apparatus, a fluid pressure operated pump adapted to receive a liquid at relatively low pressure and discharge it at a relatively high pressure, a first discharge connection leading from the high pressure part of said pump, a second discharge connection leading from a low pressure power fluid discharge of said pump in combination with a composite nozzle having a relatively small opening connected to said first discharge connection for the purpose of discharging a strong cutting jet of high pressure liquid, and an adjacent relatively large nozzle opening directed toward substantially the same area as said high pressure nozzle opening and connected to said second discharge connection from said pump to discharge a low pressure annular flushing stream around said high pressure jet.

2. In a washing apparatus, a fluid pressure operated pump including means for simultaneously providing a first fluid supply at relatively high pressure and small volume and a second fluid supply at relatively low pressure and great volume, said pump including means whereby the fluid medium for operating the pump at low pressure is passed on to serve as said second fluid supply and a composite nozzle comprising a relatively small discharge port connected to said high pressure fluid supply and a relatively large discharge port connected to said low pressure fluid supply, whereby said first mentioned port will be caused to discharge a strong cutting stream of relatively small volume, and said second mentioned port will be caused to discharge a relatively weak flushing stream of relatively large volume to wash away the materials loosened by the cutting stream.

3. In a washing apparatus, means for simul-

tanuously providing a fluid supply at relatively high pressure and small volume and another fluid supply at relatively low pressure and great volume, and a composite nozzle comprising a central relatively small discharge port connected to said high pressure fluid supply and a relatively large annular discharge port connected to said low pressure fluid supply and surrounding said central port and extending somewhat beyond the end of said small port, both of said ports being arranged so as to discharge fluid in substantially the same direction, whereby said central port will be caused to discharge a strong cutting stream of relatively small volume, and said annular port will be caused to discharge a relatively weak flushing stream of relatively large volume toward substantially the same area to wash away the materials loosened by the cutting stream.

4. In a washing apparatus, a fluid pressure operated pump including means for simultaneously providing a first fluid supply at relatively high pressure and small volume and a second fluid supply at relatively low pressure and great volume, said pump including means whereby the fluid medium for operating the pump at low pressure is passed on to serve as said second fluid supply, and a composite nozzle comprising a relatively small discharge port connected to

said high pressure fluid supply, and a relatively large discharge port connected to said low pressure fluid supply and concentric with said small discharge port, whereby said first mentioned port will be caused to discharge a strong cutting stream of relatively small volume, and said second mentioned port will be caused to discharge a relatively weak flushing stream of relatively large volume to wash away the materials loosened 10 by the cutting stream.
